UNITED STATES PATENT OFFICE

ROBERT BACK, OF CHICAGO, ILLINOIS, ASSIGNOR TO THE WAHL COMPANY, OF CHICAGO, ILLINOIS, A CORPORATION OF DELAWARE

DESIGN FOR A FOUNTAIN PEN

Application filed December 20, 1930. Serial No. 38,040. Term of patent 14 years.

To all whom it may concern:

Be it known that I, ROBERT BACK, a citizen of the United States, residing at Chicago, in the county of Cook and State of Illinois, have invented a new, original, and ornamental Design for Fountain Pens of which the following is a specification, reference being had to the accompanying drawing forming part thereof.

Fig. 1 is a front elevation of a fountain pen showing my new design, the dominant feature of which is the contour of the clip.

Fig. 2 is a side elevation of the same.

I claim:

The ornamental design for a fountain pen substantially as shown and described.

ROBERT BACK.
